UNITED STATES PATENT OFFICE.

JOHN GUSTAV EKLUND, OF ST. JOSEPH, MICHIGAN, ASSIGNOR TO ST. JOSEPH IRON WORKS, OF ST. JOSEPH, MICHIGAN, A CORPORATION OF MICHIGAN.

BASKET-COVER-STITCHING MACHINE.

1,334,742.

Specification of Letters Patent. Patented Mar. 23, 1920.

Application filed June 7, 1919. Serial No. 302,421.

To all whom it may concern:

Be it known that I, JOHN G. EKLUND, a citizen of the United States, residing at St. Joseph, in the county of Berrien and State of Michigan, have invented a new and useful Basket-Cover-Stitching Machine, of which the following is a specification.

This invention has reference to machines for making hoop covers for stave bushel baskets, and its object is to provide a machine whereby the covers may be made of staves and a joining hoop firmly stapled together with the staples all properly positioned with reference to the hoop so as to enter the material of the hoop at a predetermined distance from the outer margin thereof so that all staples will be embedded in the hoop.

A basket hoop is made of relatively thin material bent upon itself into hoop form with the ends joined by overlapping in the usual manner. With such a hoop there is not only variation in the circular contour but in the thickness of the stock. For these reasons it frequently happens that the staples employed to secure the staves onto the hoop may entirely miss the hoop and therefore have the points exposed where they may do harm to the person handling the covers or in other manner.

In accordance with the invention the hoop is mounted upon a rotatable carrier and the stapling head is held in a certain relation to the hoop so mounted that the staples will enter the hoop about midway of its thickness and consequently find a backing of wood. This is accomplished by controlling the stitching or stapling mechanism in such manner that it has imparted to it a normal tendency toward the hoop and holds the position so determined, with respect to the hoop, while the stitching mechanism and hoop are maintained in the determined relative position until the stitching or stapling is completed, wherefore, the staples will be driven into the hoop not only in spaced relation to each other but in constant spaced relation to the outer edge of the hoop. By such means the staples are always driven into the wood of the hoop and no staple points are exposed, nor is there liability of splitting the hoop as might occur if the staples varied in distance from the edge portion of the hoop.

The invention will be best understood

from a consideration of the following detailed description taken in connection with the accompanying drawings forming part of this specification, with the understanding, however, that the invention is not confined to any strict conformity with the showing of the drawings, but may be changed and modified so long as such changes and modifications mark no material departure from the salient features of the invention as expressed in the appended claims.

In the drawings:

Figure 1 is an elevation of a portion of a stitching or stapling machine equipped with the invention.

Fig. 2 is a plan view of the structure shown in Fig. 1, but omitting distant parts.

Referring to the drawings, there is shown a post 1 which may be considered as the post or standard of a known form of stapling machine. Journalized on the post is a shaft 2 provided with an elongated journal bearing 3 carried by a bracket 4 fast to the post. The shaft 2 is provided with a sprocket wheel 5 and a ratchet or lock wheel 6 whereby the shaft 2 may be given a step-by-step forward movement. At the end of the shaft 2 remote from the sprocket wheel 5 it has fast to it a bevel gear wheel 7 meshing with another bevel gear wheel 8 carried by an upright shaft 9 extending through a journal bearing 10, in turn carried by a prolongation 11 of the bracket 4. The upper end of the shaft 9 has fast to it a turn-table 12 having a marginal exterior ledge or flange 13 designed to receive and support a hoop 14, which hoop may consist of an ordinary basket hoop needing no particular description. It is the purpose of the machine to secure staves 15 in suitably spaced relation to the hoop 14 so as to produce a cover of any suitable size, say stave bushel basket size, although the invention is not necessarily confined to such particular size of container. The cover is provided with a cross piece 16 at right angles to the staves 15 so as to not only stiffen the cover but provide a convenient handling means therefor.

Mounted on the post 1 is a head 17 carrying the basic portion 18 of an oscillatory stapling head 19, which latter may be of approved pattern and needs no particular description. The stapling head is of a character whereby staples, such as shown at 20 in

Fig. 2, may be driven at determined intervals through the staves 15 where overlying the hoop 14 so that the staves are properly secured to the hoop. The stapling head is so mounted that it may be swung over the turn-table 12 or away therefrom and when over the turn-table is then so located that the staples are driven through the staves into the hoop between the side walls of the hoop and at a certain distance from the outer wall.

The basic portion 18 of the stapling head 19 carries an arm 21 to which is secured one end of a spring 22, the other end of the spring being made fast to a bracket 23 secured to the upper face of the head 17, so that the base 18 may move about an upright axis, with the spring 22 tending at all times to move the stapling end of the head 19 toward the turn-table 12. The arm 21 is shown in Fig. 2 as in radial relation to the axis of oscillation of the base 18 and in the path of the arm 21 is one end of a spring 24 fast to the upper face of the head 17. The spring 25 or catch 24 is a leaf spring and its free end is formed with a notch or depression 25 so arranged that the arm 21 will snap into the depression, thereby holding the stapling head in the inactive position but in such manner that the stapling head may be readily released by hand, whereupon the spring 22 will move the stapling head into active position. To determine such active position the stapling head has a bracket 26 fast to and carried thereby and on this bracket is mounted a roller 27 or round-nosed piece of steel or other suitable gage means so positioned as to bear against the outer edge of a hoop 14 when mounted on the turn-table 12. Carried by a comparatively rigid part of the machine is an anvil 28, shown in Fig. 1 as supported by a bracket 29 on fixed parts of the machine. The anvil 28 is adjustable up and down by being provided with a screw stem 30 and a lock nut 30 but may be otherwise constructed, the purpose of the anvil being to provide an under support for that part of the table 12 over which the staple part of the stapling head is located. In order to aid in the manipulation of the stapling head there is provided a handle 32 so situated as to be in ready reach of an operator, so that the stapling head may be moved out of operative position when it is desired to place a cover in position for stapling or to remove a finished cover. The roller 27 takes care of the proper placing of the staples with respect to the axis of rotation of the cover while the machine automatically spaces the staples with respect to the staves circumferentially of the head and drives them.

It is to be understood that the invention is applicable to that type of stitching machines for making hoop covers for stave bushel

baskets in which the turn-table is capable of oscillating toward and from the stitching head which is then held against such oscillatory movements, and in the claims the statement that the table and stapling head are relatively movable, is intended to be broad enough to cover either type of machine.

What is claimed is:—

1. A machine for stitching or stapling the staves and hoops of stave basket covers together, comprising a stapling head, a table for carrying a hoop and receiving staves placed thereon, a mounting for the stapling head, with the table and stapling head relatively movable one toward the other, and guiding means for determining the relative placing of the stapling head and table to drive staples into one edge of the hoop between opposite faces thereof. 85

2. A machine for stitching or stapling the staves and hoops of stave basket covers together, comprising a stapling head mounted to oscillate about an upright axis, a rotatable table for supporting a hoop with staves laid thereon, and a guide roller on the stapling head and movable therewith into engagement with a hoop on the table to follow the contour of the hoop and maintain the relation of the stapling head to the hoop. 95

3. A stapling machine provided with a stapling head mounted to oscillate about an upright axis, means for constraining the head in one direction, a rotatable table in position to be overridden by the head under its normal tendency, said table being adapted to receive and hold a hoop with staves thereon, and means for limiting the approach of the head toward the table whereby to locate the driving position of the staples within the margins of the walls of the hoop. 100

4. In a stapling machine, means for carrying a hoop and staves thereon to be stapled together, a stapling head mounted to one side of the hoop carrying means, and means determined by the hoop for locating the stapling head with relation to the hoop to cause staples to pass through the staves and enter the hoop intermediately of the thickness of the hoop. 115

5. In a stapling machine, a rotatable carrier for a hoop and staves located thereon, a stapling head mounted to oscillate toward and from the hoop to a position over the latter, and means controlled by the hoop for determining the approach of the stapling head toward the hoop, whereby staples may be driven through the staves into the hoop intermediately of the thickness of the hoop. 120

6. In a stapling machine, a rotatable hoop carrier for receiving a hoop and staves supported by the hoop, a stapling head movable toward and from the hoop into and out of operative position over the hoop, means for 130

constraining the stapling head toward the hoop, and a stop on the stapling head in position to engage the hoop and thereby control the movement of the stapling head toward the hoop, whereby staples may be driven through the staves into the hoop with the position of the staples crosswise of the thickness of the hoop automatically determined by the stop means.

10 7. In a stapling machine, a rotatable hoop carrier for receiving a hoop and staves supported by the hoop, a stapling head movable toward and from the hoop into and out of operative position over the hoop, means for constraining the stapling head toward the hoop, and stop means on the stapling head in position to engage the hoop and thereby control the movement of the stapling head toward the hoop, whereby staples may be driven through the staves into the hoop with the position of the staples crosswise of the thickness of the hoop automatically determined by the stop means.

25 8. In a stapling machine, a rotatable hoop carrier for receiving a hoop and staves supported by the hoop, a stapling head movable toward and from the hoop into and out of operative position over the hoop, means for constraining the stapling head toward the hoop, and stop means on the stapling head in position to engage the hoop and thereby control the movement of the stapling head toward the hoop, whereby staples may be driven through the staves into the hoop with the position of the staples crosswise of the thickness of the hoop automatically determined by the stop means, said stop means comprising a roller for engaging the outer wall of the hoop, and a support for the roller carried by the stapling head.

30 9. In a stapling machine, a rotatable hoop carrier for receiving a hoop and staves sup-

ported by the hoop, a stapling head movable toward and from the hoop into and out of operative position over the hoop, means for constraining the stapling head toward the hoop, and stop means on the stapling head in position to engage the hoop and thereby control the movement of the stapling head toward the hoop, whereby staples may be driven through the staves into the hoop with the position of the staples crosswise of the thickness of the hoop automatically determined by the stop means, said stop means being carried by the stapling head.

35 10. In a stapling machine, a rotatable table for carrying a hoop and staves thereon, a stapling head mounted to oscillate toward and from the table, a roller on the head movable into and out of engagement with a placed hoop to position the stapling head to drive staples through the staves into the hoop intermediate of the thickness of the hoop, means constraining the stapling head toward the hoop, an arm carried by the head and to which the constraining means is attached, and a catch on a fixed part of the machine in the path of the arm and shaped to receive and temporarily hold the arm when the head is in the inactive position.

40 11. In a stapling machine, a stapling head and a carrier for a hoop and staves to be stapled together, the head and carrier having a normal constraint to approach, and means on the head for engaging the hoop to control and maintain the position of the head with relation to the hoop, whereby the staples are driven through the staves into the hoop intermediately of the thickness of the latter.

45 In testimony that I claim the foregoing as my own, I have hereto affixed my signature.

JOHN GUSTAV EKLUND.
